(57) **CLAIM**

The ornamental design for a cutting tool, as shown and described.

DESCRIPTION

FIG. 1 is a front view of a cutting tool in accordance with Embodiment 1 of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 shows a cutting tool in an environment of use thereof;

FIG. 12 is a front view of a cutting tool in accordance with Embodiment 2 of the present design;

FIG. 13 is a rear view thereof;

FIG. 14 is a right side view thereof;

FIG. 15 is a left side view thereof;

FIG. 16 is a top view thereof;

FIG. 17 is a bottom view thereof;

FIG. 18 is a first perspective view thereof;

FIG. 19 is a second perspective view thereof;

FIG. 20 is a third perspective view thereof;

FIG. 21 is a fourth perspective view thereof; and,

FIG. 22 shows a cutting tool in an environment of use thereof.

The broken lines seen in FIG. 11 and FIG. 22 are for the purpose of showing environmental structure, and form no part of the claimed design.
